BOX CONSTRUCTION

Walter F. Newhouse, Benton Harbor, Mich.

Application December 17, 1943, Serial No. 514,601

3 Claims. (Cl. 217—15)

This invention relates to a box which is constructed with the several walls bound together with wires which are stapled to the walls and serve as hinges during the assembly of the parts. The invention relates more particularly to means for securing the end or head walls of the box to the side walls thereof.

An object of the invention is to provide simple and efficient means for readily, securely and economically fastening the end walls of foldable boxes and crates in position, especially those made of wood veneer, solid fibre, corrugated fibre board, or combinations of wood veneer and fibre board, and other materials and substitutes therefor.

A further object of the invention is to provide a box construction with side walls having reinforcing members or cleats formed with cutaway portions and adapted to receive a loop which may be nailed, stapled or otherwise secured in fastening position within the side walls of the box, thus eliminating projecting clips and other objectionable fastening means heretofore employed in box construction.

Another object of the invention is to provide a construction wherein a loop may be in the form of a separate staple driven into the end wall, or a loop as a part of a binding wire, or a loop connected with another loop.

Additional objects, advantages and capabilities inherent in this invention will become readily apparent from the description thereof which follows.

This invention further resides in the combination, construction and arrangement of parts illustrated in the accompanying drawings, and while there is shown therein preferred embodiments of the invention, it is to be understood that the same are susceptible of modification and change without departing from the spirit of the invention.

The accompanying drawings illustrate a selected embodiment of the invention, and the views therein are as follows:

Fig. 1 is a perspective view of a box embodying the invention with portions of the side walls broken away to show the fastening means in place;

Fig. 2 is a horizontal sectional view along the line 2—2 of Fig. 1;

Fig. 3 is a sectional view along the line 3—3 of Fig. 2;

Fig. 4 is a perspective view of a portion of one form of the invention;

Fig. 5 is a perspective view of a reinforcing cleat of a side wall and a portion of an end wall

in position for assembly to form a box embodying the invention;

Fig. 6 is a perspective view of parts of a box embodying the invention prior to assembly;

5. Figs. 7, 8, 9 and 10 show a portion of an end wall embodying different modifications of a part of the invention in perspective.

The particular construction herein disclosed for the purpose of illustrating the invention comprises a box made from a box blank having spaced enclosing side walls, the enclosing side walls including a bottom 11, a top 12, and side walls 13, which may be of wood veneer and are alike except that they may be of different dimensions. The opposed walls may be of like dimensions, but they could be of other and various configurations. Each side wall, including the top and the bottom, is provided with a reinforcing cleat 14 extending along its edge at each end.

15. These cleats may be suitably secured to the inner face of the wall as by staples 15, and have their ends bevelled, correspondingly, generally to form a rectilinear fit when assembled, as shown at 16 in Figs. 1 and 5. The cleats may be tongued and grooved, or they may comprise any other conventional or suitable joint construction instead of the specific bevel construction shown. The side walls, including the top and bottom, are secured together by means of spaced wires 17 which are

20. secured to the walls by means of the staples 15 which also serve to secure the cleats 14 to the walls. The wires 17 are of sufficient length to permit tying or twisting their opposed ends together or arranged with male and female loops 17a and 17b at the ends of the wire, Fig. 6, to complete the assembly of a box, such as shown at 27 in Fig. 1.

25. The end walls 18, which also may be of wood veneer, may have reinforcing strips 19 along opposed edges as shown in Figs. 1 and 6. The end walls 18 are also provided with spaced fastening means adapted to be received in correspondingly spaced cutaway portions 20 provided in the

30. face of the reinforcing members 14 adjacent the side walls which they respectively reinforce. The fastening means may be in the form of a staple 21 driven into the reverse side of the end wall

35. and turned about the lateral edge of the end wall as shown in Figs. 2, 4 and 5. They may be in the form of loops 22 made by turning opposed ends of a flexible binding material or wire upon themselves as shown in Fig. 9, or in the form of a single loop 23 as shown in Fig. 8, or in the

40. form of separate loops 24 stapled to the end wall

as shown in Fig. 7. In Figs. 7, 8 and 9 the wire is preferably stapled to the reverse side of the end wall as shown at 25, and the loop is turned about the lateral edge of the end wall. Other forms of fastening means, such as a metallic hook, or metal stamping of hook or loop form, or metal strapping, may also be employed.

When the parts of the box are assembled, as shown in Figs. 1, 2 and 3, a nail 26 or other fastening means, for example, a staple, may be driven through the overlying side wall and the loop 21, or 22, 23 or 24, as the case may be, to fasten the parts in assembled position, provision being made for the loops of one side of the box end to be secured to the box side and thereby providing for both ends of the box to be assembled into the box blank in knock-down condition, whereby all parts (box blank and ends), are contained as a unit at the box factory of manufacture.

It will be readily appreciated that the means thus described provide a simple, economical, trim, and efficient fastening which may be readily applied to boxes and crates. The employment of the loops 21 and 24 in the manner described permits a considerable saving of wire. The employment of the loops 22 and 23 permits the use of a wire of lighter gauge as it need not be driven into the end wall in staple-like manner or subjected to as many turns as in the case of the loop 21. The arrangement in the present invention of a loop secured in a cutaway portion of a side wall cleat by means of a nail or other metal fastener driven through the side wall and into the cleat within the loop also makes possible the elimination of projecting clips or loops which have heretofore been employed, as the cutaway portion is positioned so that the loop does not extend through the cleat but is covered by the adjacent overlying portion of the side wall. This is a distinct advantage for such fastening means which project are susceptible to disarrangement by snagging or catching adjacent objects, with consequent injury to the box and contents as well as other merchandise. The binding wire, strap or other member 17 may be attached to the flush sides of the end walls 18 and provided with loops 28 which extend perpendicular, or substantially so, from the faces of the reinforcing strips 19, as shown in Fig. 10.

Changes may be made in the form, construction and arrangement of the parts without departing from the spirit of the invention, and the right is hereby reserved to make all such changes as fairly fall within the scope of the following claims.

The invention is hereby claimed as follows:

1. A collapsible wirebound box of the character

described comprising side walls and end walls, cleats attached to said side walls, and means for attaching said end walls in fixed position with respect to said side walls comprising a shallow notch formed in an exterior edge of a cleat and extending outwardly from an inner side of a cleat a distance less than the thickness of a cleat to provide an opening recess interiorly of the cleat, a looped fastener secured to an inner side of a said end wall in position to extend substantially perpendicularly outward from the plane of an end wall and to be directly received in said opening recess, and a fastening member driven through a side wall, through the looped fastener and into the cleat at the said recess to secure rigidly and fixedly the end wall to the cleat and a side wall.

2. A collapsible wirebound box of the character described comprising side walls and end walls, cleats attached to said side walls, and means for attaching said end walls in fixed position with respect to said side walls, comprising a shallow notch formed in an exterior edge of a cleat and extending outwardly from an inner side of a cleat a distance less than the thickness of a cleat to provide an opening recess interiorly of the cleat, a bendable tongue-like member secured to an inner side of a said end wall in position to extend substantially perpendicularly outward from the plane of the end wall and to be directly received in said recessed opening, and a fastening member driven through a side wall, the tongue-like member and into the cleat at the recess to secure rigidly and fixedly the end wall to the cleat and a side wall.

3. A collapsible wirebound box of the character described comprising side walls and end walls, cleats attached to said side walls, and means for removably attaching said end walls in fixed position with respect to said side walls, comprising shallow notches formed in exterior side edges of the cleats outwardly from the inner surfaces of said cleats a distance less than the thickness of the cleats to provide recessed openings positioned interiorly of the outer edges of the cleats and extending substantially in longitudinal planes, bendable tongue-like members secured to the inner faces of the said end walls in position to extend substantially perpendicularly outward from the plane of the end walls and to be directly received in said recessed openings, and fastening means driven through the side walls, the tongue-like members and the cleats at the recesses after insertion through said recessed openings to secure rigidly and fixedly the end walls to the cleats and side walls with all portions of the tongue-like members positioned interiorly of the ends of said box.

WALTER F. NEWHOUSE.
